BREATHING MASK

Silas A. Morehouse, Los Angeles, Calif.

Application February 28, 1942, Serial No. 432,726

8 Claims. (Cl. 128—141)

This invention relates broadly to breathing masks and associated gear for use particularly in supplying oxygen to aviators, although the apparatus involves features of construction that may be useful in related equipment, such as gas masks.

An object of the invention is to provide breathing mask equipment that is comfortable, compact, and relatively free from loose, dangling parts, while at the same time satisfying the service requirements of a breathing mask.

Another object is to provide a breathing mask assembly having a gas-supplying or purifying chamber carried on the head of the wearer in such a manner as to be comfortably supported and out of the way.

Another object is to provide breathing mask equipment adapted to be worn entirely on the head and provide an unusual amount of protection to the head of the wearer in the event of a crash.

Another object is to provide an aviator's oxygen mask adapted to be supplied with oxygen through a connecting tube from a stationary tank, in which the aviator's head cannot be pulled or jerked by the connecting tube should the aviator have to leave this airplane under emergency conditions.

Another object is to provide an oxygen mask so constructed as to adapt it for use either with or without goggle lenses for the eyes of the wearer.

Another object is to provide for heating the oxygen supplied to an oxygen mask.

Other more specific objects and features of the invention will become apparent from the description to follow of a specific embodiment of the invention.

Oxygen masks for aviators are not broadly new. The essential elements of such a mask include a facepiece adapted to cover and seal about the nose and mouth of the wearer, an expansible and contractible rebreathing bag connected to the facepiece, and a connection to a source of oxygen. The oxygen source supplies a relatively slow, continuous stream of oxygen sufficient to satisfy the user's oxygen requirements but not equal to the rate of inhalation of the user. The purpose of the rebreathing bag is to provide a reservoir in which a certain amount of breathed gas and oxygen from the oxygen source is stored during exhalation and then supplied to the facepiece during inhalation with relatively little resistance so that the user is not forced to exert abnormal muscular effort in order to breathe.

A relatively important problem in the design of oxygen masks has been to provide a satisfactory construction of the rebreathing bag. One of the simplest methods first adopted was to employ a simple rubber bladder suspended from the facepiece in front of the chest of the user, as disclosed in United States patent to Heidbrink 2,448,349.

Another method, disclosed in United States patent to Heidbrink 2,185,997, is to position an ordinary rubber bladder on the top of the head of the user, somewhat in the fashion of a plume on the top of a helmet.

Such constructions satisfy the gas-storing requirements, but have disadvantages from a mechanical standpoint in that the bladders are unprotected and subject to damage and may become entangled with other apparatus.

My mask differs essentially from the prior constructions mentioned in that the rebreathing bag is enclosed and so shaped that it forms a compact unit mounted on the head of the user in such a way as not to extend in any direction where it would interfere with the normal movement of the head. My design also substantially eliminates the loose conglomeration of tubes and wires leading to the headgear of an aviator, which headgear must include, in addition to the oxygen supplying equipment, the usual microphone and earphones for radio communication.

Referring now to the drawing:

Fig. 1 is a side view of an oxygen mask in accordance with my invention, shown mounted in position on the head of a user;

Fig. 2 is a horizontal section, taken through the rebreathing reservoir of the mask shown in Fig. 1;

Fig. 3 is a detail, vertical section, taken substantially in the plane III—III of Fig. 2;

Fig. 4 is a detail view, partly in section, of a portion of the cord for making gas and electric connection to the mask;

Fig. 5 is a detail section, taken substantially in the plane V—V of Fig. 1;

Fig. 6 is a detail section, taken substantially in the plane VI—VI of Fig. 1;

Fig. 7 is a detail section showing the shape of the face-contacting edge of the mask; and

Fig. 8 is a detail elevation view showing an orifice in the facepiece for insertion of a drinking tube.

Referring, first, to Fig. 1, the apparatus therein disclosed comprises a helmet 10 adapted to fit on the head of the user, and a facepiece 11 adapted to cover the nose and mouth and form a gas-tight fit against the face. The helmet 10

comprises an upper portion 12 adapted to fit snugly against the top and back of the head like a skullcap, with extensions or flaps 13 extending over the ears and portions of the cheeks. A chinstrap 14 may connect to the lower portions of the flaps 13 for holding them snugly against the sides of the head. The flaps 13 contain pockets for supporting earphones 15 against the ears.

The facepiece 11 may comprise an inner, moulded rubber cup 16, shaped to fit against the face around the nose and mouth, and held in place by an outer band or harness 17 which overlies the cup 16 and is secured by straps 18 and 19 to the side portions or flaps 13 of the helmet 10. The straps 18 and 19 may be provided with connecting buckles 20 to permit adjustment.

I prefer to provide the face cup 16 with a relatively wide face-contacting lip 21, as shown in Fig. 7, the face-contacting surface of lip 21 being preferably provided with alternate furrows 22 and ridges 23 to secure a more nearly gas-tight seal with the face.

The facepiece 11 may be provided with suitable means for supporting a microphone 24 in front of the mouth of the user. The exact construction of the microphone mounting does not constitute a part of the present invention and it may be constructed as described in my co-pending application Serial No. 328,491, filed April 8, 1940, on an Oxygen mask.

A breathing tube 25 extends from the face cup 16 through an opening provided therefor in the band 17 to a rebreathing reservoir on the helmet 10. This tube 25 may be of soft rubber, corrugated circumferentially, so as to reinforce it against collapse in response to the suction that is produced when the user inhales. The tube 25 extends rearwardly and upwardly, well away from the nearest eye, so that it does not obstruct the vision of the wearer, and lies close against the cheek so that it is not likely to become entangled with anything.

Referring now to Figs. 1, 2 and 3, the helmet 10 has formed on the side thereof a bulbous, roughly annular extension extending all the way around the head. The greater portion of this extension is hollow and forms a chamber for a rebreathing bag or bladder 28. The front portion of the bulbous extension contains padding 29, such as hair, to protect the head in the event of crash, and to also serve as a visor to shade the eyes of the user.

That portion of the bulbous extension containing the rebreathing bag 28 is of substantially horseshoe shape, in plan, and may be defined by an outer wall 30 of relatively stiff leather, or similar material, secured at its edges to the skullcap portion 12 of the helmet, the portion 12 serving as the inner wall of the chamber containing the rebreathing bag 28. To facilitate inspection or repair of the rebreathing bag, the lower edge of the casing 30 may be secured to the portion 12 of the helmet by a slide fastener 31. The breathing tube 25 extends through an aperture provided therefor in the casing 30 and connects to the rebreathing bag 28 adjacent the forward end thereof. An oxygen tube 32 extends through an aperture provided therefor in the casing 30 and connects to the rebreathing bag 28 at a point displaced rearwardly from the breathing tube 25.

The wall 30 may advantageously be formed of leather with the fur left on, to provide thermal insulation and help keep the air in the rebreathing bag warm. This air is warmed to a certain

extent by conduction from the head of the wearer through the wall 12.

Respiration of the user causes the rebreathing bag 28 to alternately fill and collapse within the casing 30. To permit free contraction and expansion of the rebreathing bag, a number of vent holes 33 may be provided in the casing 30 adjacent the lower edge thereof.

It is also desirable to provide a permeable wall 10 in the rebreathing bag to permit auxiliary air to enter when the rebreathing bag is empty, and such permeable wall may be formed by a patch 34 (Fig. 3) of porous sponge rubber secured to the rebreathing bag 28 overlying a hole 35 therein. A number of small vent holes 36 may be provided in the casing 30 overlying the permeable member 34.

In operation, a continuous stream of oxygen is supplied through the tube 32 to the rebreathing bag 28, so that the latter becomes filled with oxygen and exhaled gases before the end of each expiration. After the bag 28 has filled, a portion of the last exhaled air escapes through a conventional exhaust valve 45 (Fig. 2) which is connected to and extends laterally from the face cup 16. This valve 45 is of conventional construction employed in gas masks, and the like, for years, and simply functions as a check valve to permit escape of air in response to excess pressure within the cup while preventing the entry of air.

The front or visor portion 38 of the bulbous extension on the helmet may be formed of soft leather, and stuffed with hair or other suitable padding material, as previously indicated. It is stuffed sufficiently tightly to retain its shape in ordinary use, but will yield and cushion the head of the user against blows from the front, such as might result in an airplane crash. It preferably extends forwardly beyond the microphone 24 so that if the user's head is thrown forwardly against the instrument board of an airplane, the stuffed visor portion will stop movement of the head toward the instrument board before the microphone can contact the instrument board and be forced back into the user's face.

The visor portion 38 is flush with and joined to the rebreathing case 30 at its rear end and is secured at its upper and lower edges to the skullcap portion 12 of the helmet.

The oxygen supply tube 32 extends away from the helmet to a suitable oxygen supply system. Likewise electrical connections extend from the microphone 24 and the earphones 15. In accordance with the present invention, I combine the oxygen tube and the electrical wires into a single composite cord 40 which extends to an anchor clip 41 adapted to be secured to one of the shoulder straps 42 of a conventional parachute harness. The anchor member 41 makes releasable connection to a second cord 50 which may be extended to any suitable distance to complete connection to an oxygen supply system and to the radio system of which the microphone 24 and the earphones 15 constitute parts.

The upper end of the composite cord 40 is secured, as by a strap 51, to the helmet 10 at the rear portion of the head of the wearer. From this point the oxygen tube 32 extends to the rebreathing bag, and the wires extend to the microphone and earphones. Thus the microphone wires 52, which may consist of two insulated conductors formed into a single cord, extend through 70 a conduit 53 provided therefor in the band 17 of

the facepiece. The cord 54, going to the left earphone, is very short and does not need to be anchored down. The cord 54, going to the right earphone, preferably extends around the back of the head immediately below the case 30 and is preferably extended through a tunnel or loops 55 to hold it snugly against the helmet.

The composite cord 40 may be formed by laying the various electrical conducting wires about the oxygen tube 32 in a single layer, as shown in the lower portion of Fig. 4, the whole being enclosed in an outer casing 56, which may be of woven fabric or rubber.

The anchor clip 41 may be constructed as shown in Figs. 5 and 6 and comprises a relatively rigid clip 57 into which the parachute shoulder strap 42 can be forced through an opening 58 at one side of the clip. The outer wall 59 of the clip has secured thereto a casing member 60 containing a projecting tube 61 over the upper end of which the oxygen tube 40 is slipped, and a plurality of electrical conducting elements 62 to the upper ends of which the various electrical wires 63 are individually connected as by pins 64 on the ends of the wires and pin jacks 64^a formed in the upper ends of the connectors 62. The case 60 is, of course, constructed of electrical insulating material so as not to short circuit the electrical conductors 62. At the lower end of the case 60 the conductors 62 may terminate in pin jacks 65 which receive connecting pins 66 on the ends of wires 67 forming a part of the cable or cord 50 which extends away from the body of the person using the mask. The oxygen tube 68 in the cord 50 is slipped over the tube 61 in the anchor member 41. As a result of the construction described, the cord 50 can be jerked away from the anchor member 41 in an emergency without transmitting the tug to the cord 40 extending to the apparatus on the head of the user.

I find that it is sometimes desirable when flying at extreme altitudes in an airplane without adequate heating facilities, to supply some heat to the oxygen because of the fact that the oxygen is cooled even below the low temperature existent at high altitude, by expansion as it leaves the pressure tank in which it is stored. I therefore provide in the cord 40 an electrical heating device for warming the oxygen as it flows to the mask. The construction of the heating device is disclosed in Fig. 4. It comprises a metal nipple 70 inserted in the oxygen tube 32 and surrounded by an electrical heating coil 71. The coil 71 may be separated from the metal nipple 70 by a thin layer of electrical insulating material 72, such as mica, and is itself formed of wire insulated with heat-resistant electrical insulation of any known type. The coil is surrounded by a thin layer 73 of thermal insulation to reduce wastage of heat by radiation. The coil 71 is connected at opposite ends to a pair of wires from the plurality of wires 63 in the cord, which wires may be connected at their remote ends (by a pair of conductors in the cord 50) to any suitable source of current, such as the usual electric battery of an airplane. Of course a switch may be inserted in the heating circuit at any convenient point, but since it is not essential, and would be of conventional construction, it is not disclosed in the drawing.

Electrical connections to the microphone 24 and the earphones 15 are preferably made by means of screw connections, so that the microphone and earphones can be removed from the

helmet assembly for testing or servicing without removing the connecting wires from the helmet.

The band 17 is provided with detachable fasteners on the right side (not visible in the drawing) positioned similarly to the buckles 20 on the left side, so that the facepiece 11 can be loosened and swung away from the face without interference by the breathing tube 25 and the electrical leads 52 extending to the microphone. After the facepiece has been released as described, the chin strap 14 on the helmet can be released and the helmet removed from the head. The helmet is put on by reversing the procedure; namely, first applying the helmet portion 10 to the head and securing the chin strap 14, and then locating the facepiece in proper position in front of the face and securing the fasteners on the right side thereof, which fasteners correspond to the buckles 20 shown in Fig. 1.

It is sometimes desirable, particularly when flying at great altitudes during the daytime, to have dark goggles to shield the eyes from the intense light. It is awkward to wear conventional goggles with oxygen mask equipment, and in accordance with the present invention, I provide clips 80 on the face cup 16, adapted to receive the lower edges of a pair of goggle lenses 81 and support them in proper position in front of the eyes of the user. These lenses 81 may be of glass or of unbreakable plastic material and may be readily removed at any time by simply lifting them out of the supporting clips 80.

When an aviator is required to fly at high altitudes for long periods of time, it is often desirable that he be able to drink. Heretofore it has been impossible to do this without removing the oxygen mask. However, in accordance with the present invention, I make it possible for the aviator to imbibe liquid through a drinking tube without removing his oxygen mask. Thus, as shown in Figs. 2 and 8, the rubber face cup 16 has an inwardly extending nipple 30 formed therein immediately to one side of the microphone 24, this nipple having a pair of cross slits 91 and 92 therein, through which a drinking tube can be passed to the mouth of the aviator. The rubber walls of the nipple will return to normal, closed position when the drinking tube is withdrawn.

Various changes from the exact construction disclosed may be made without departing from the invention, and the latter is to be limited only as set forth in the appended claims. For instance, the general construction disclosed would be useful in a gas mask, the air-purifying chemicals being contained in the rebreathing chamber, which might, to advantage, then be extended all the way around the head, the stuffed visor being eliminated.

I claim:

1. A breathing apparatus adapted to be supported on and movable with the head of a person, and comprising: a first means for effecting a breathing connection with a breathing orifice of said person, and a second means defining a chamber of substantial cubic content, cooperating with said first means to supply breathing gas thereto, said second means including skullcap member adapted to rest snugly on the top and sloping side and rear portions of the head, and a bulbous wall joined at its edges to said skullcap member and defining therewith a chamber curved longitudinally about the head in substan-

tially horizontal position with its top approximately level with the top of the head.

2. A breathing apparatus adapted to be supported on and movable with the head of a person, and comprising: a first means for effecting a breathing connection with a breathing orifice of said person, a second means defining a chamber of substantial cubic content, a conduit connecting said second means with said first means to supply breathing gas thereto, said second means including a skullcap member adapted to rest snugly on the top and sloping side and rear portions of the head, and a bulbous wall joined at its upper and lower edges to said skullcap member and extending across the back and forwardly along the sides of said skullcap and defining therewith a chamber curved longitudinally about the head, the top of said bulbous wall lying approximately in a horizontal plane level with the top of the head of said person.

3. A breathing apparatus adapted to be supported on and movable with the head of a person, and comprising: a first means for effecting a breathing connection with a breathing orifice of said person, and a second means defining a chamber of substantial cubic content cooperating with said first means to supply breathing gas thereto, said apparatus including casing means of general toroidal shape, dimensioned to rest upon the upper sloping rear and side portions of the head, and against the forehead with the top of said casing approximately level with the top of the head, the rear portion of said toroidal casing being hollow and constituting said chamber, and the front portion of said toroidal casing merging smoothly into said rear portion and containing shock-absorbing material.

4. Apparatus as described in claim 3, in which the frontal shock-absorbing portion of said toroidal casing extends forwardly and laterally above the eyes of said person to constitute a visor.

5. A breathing apparatus adapted to be supported on and movable with the head of a person, comprising: first means for effecting a breathing connection with a breathing orifice of said person, and a second means defining an expandible and retractible rebreathing reservoir connected

thereto, and means for supplying a breathing gas to said reservoir, said rebreathing reservoir comprising an outer rigid casing of longitudinally curved, tubular form adapted to lie against and be supported on the upper, sloping portions of the head, and a flexible bag positioned within said outer casing and shaped to conform thereto when fully inflated, said outer casing having vent apertures therein.

10 6. Apparatus as described in claim 5, in which said first means comprises a facial cup adapted to fit over and seal around the nose and mouth of a person, with a breathing tube extending from one side of said facial cup closely along the side of the head of the person to the adjacent side of said rebreathing reservoir, and check valve means extending laterally from the opposite side of said face cup.

7. An aviator's oxygen helmet comprising: a 20 facepiece adapted to fit over and seal around the mouth and nose of the aviator, means for securing said facepiece against the aviator's face, and goggle lenses, said facepiece being provided on opposite sides of the nose with downwardly extending pockets for receiving and frictionally gripping the lower marginal portions of said lenses for detachably supporting said goggle lenses in position in front of the eyes of the aviator.

30 8. A breathing apparatus adapted to be supported on and movable with the head of a person comprising: first means for effecting a breathing connection with a breathing orifice of said person, and a second means defining an expandible and retractible breathing reservoir connected thereto, and means for supplying a breathing gas to said reservoir, said rebreathing reservoir comprising a skullcap adapted to fit on the head, an outwardly bowed strip of relatively stiff material extending across the back and forwardly along the sides of the skullcap with the upper and lower edges of said strip fastened to the skullcap to form therewith a chamber, and an elongated flexible breathing bag disposed in said chamber.

SILAS A. MOREHOUSE.
